US0D1073962S

(12) **United States Design Patent** (10) **Patent No.:** **US D1,073,962 S**
(45) **Date of Patent:** **** May 6, 2025**

(54) **THUMB BRACE**

(71) Applicant: **SHENZHEN WEPROTEX
TECHNOLOGY PRODUCT CO.,
LTD., Shenzhen (CN)**

(72) Inventor: **Xiaoxing Zheng, Shenzhen (CN)**

(73) Assignee: **SHENZHEN WEPROTEX
TECHNOLOGY PRODUCT CO.,
LTD., Shenzhen (CN)**

(**) Term: **15 Years**

(21) Appl. No.: **29/918,999**

(22) Filed: **Nov. 30, 2023**

(51) **LOC (15) Cl. 24-02**

(52) **U.S. Cl.**

(57) **CLAIM**

The ornamental design for a thumb brace as shown and described.

DESCRIPTION

FIG. 1 is a perspective view of a thumb brace showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the thumb brace where the thumb brace is in a configuration of use; and,

FIG. 10 is another perspective view thereof.

The broken lines in the drawings depict portions of the thumb brace that form no part of the claimed design.

1 Claim, 10 Drawing Sheets
